UNITED STATES PATENT OFFICE.

JOHN E. WILLIAMS AND WILLIAM H. MITCHELL, OF SALLISAW, OKLAHOMA.

COMBINED RAILWAY-TIE AND RAIL-FASTENER.

1,186,356.

Specification of Letters Patent.

Patented June 6, 1916

Application filed January 21, 1916. Serial No. 73,340.

To all whom it may concern:

Be it known that we, JOHN E. WILLIAMS and WILLIAM H. MITCHELL, citizens of the United States, residing at Sallisaw, in the county of Sequoyah and State of Oklahoma, have invented certain new and useful Improvements in Combined Railway-Ties and Rail-Fasteners; and we do declare the following to be a full, clear, and exact description of the invention, such as will enable others skilled in the art to which is appertains to make and use the same.

This invention which relates to improvements in railway ties and rail fastening means has for its principal object the provision of a simply constructed tie which can be very easily manufactured and one which will be extremely durable.

An additional object is to provide a tie which will aid in absorbing the shocks received by the rails from the passing trains.

Still another object is to provide a tie upon which the rail carrying plate is easily attached, said plate having improved fastening means for securing the rails thereto.

With the foregoing and other objects in view the invention resides in the novel features of construction, combination and arrangement of parts which will hereinafter be more particularly described and claimed and shown in the drawings wherein:

Figure 1 represents a side elevation of the improved tie showing a pair of rails mounted thereon; Fig. 2 is an end view of the tie, the rail being shown in elevation; Fig. 3 is a horizontal sectional view taken on the line 3—3 of Fig. 1; Fig. 4 is a vertical transverse section taken on the line 4—4 of Fig. 1; Fig. 5 is a detail vertical section on the line 5—5 of Fig. 2; Fig. 6 is a perspective view of the tie; Fig. 7 is a bottom plan view of the rail attaching plate; Fig. 8 is a detail perspective view of the rail attaching plate, the rail fastening members and the cushioning member for the same arranged in juxtaposition.

In the accompanying drawings we have illustrated our invention in its preferred form, and in several of the figures shown, ordinary railway rails R carried by the tie plate portion of the invention. The tie 1 is formed of a single piece of spring steel, pressed into substantially U-shape, its bottom 2 contacting with the ground while the sides 3 which extend therefrom have their free edges bent laterally outward to form

attaching flanges 4 which are arranged parallel to the bottom 2, the sides 3 preferably diverging from the bottom 2 as shown in Fig. 2. At the opposite ends of each of the rails 1 we secure a tie plate 5 upon which the rail sections R lie. These tie plates 5 are substantially rectangular in shape and have apertures in their four corners to receive fastening bolts 6 which extend through these apertures and through similar apertures alined therewith in the flanges 4 of the tie. By reference to Fig. 2 it will be evident that this arrangement provides a very light yet exceedingly strong tie structure, and it is obvious that such a tie being formed of metal will last a great deal longer than the ordinary wooden tie.

Each of the plates 5 has a rail fastener 7 formed integrally therewith substantially in its longitudinal center and to one side of its transverse center as shown in Fig. 3. Each of these fasteners comprises a boss 7' which rises from a plate and has formed integrally therewith a head 8 which contacts with the web of the rail, the active face of said head being of a width substantially equal to the distance between the rail head and the rail base, and of a length somewhat less than the width of said plate 5. The head 8 extends upwardly at an angle from the boss 7' to form a recess between it and the plate for the reception of one of the flanges of the rail. The co-operating fastener 9 on the other side of the rail is preferably readily removable from the plate 5 in order that the rail may be easily applied and is of a shape in plan view similar to the fastener 7. This fastener 9, however, has a portion 10 which corresponds to the boss 7' apertured to receive a bolt 11 which projects through an opening 12 in the plate 5. A nut 13 serves to tightly clamp the portion 10 to the plate 5. An integral boss 14 depends from the under side of the plate 5 and surrounds the opening 12 therein for the purpose of strengthening the plate at this point. The head 15 of this last mentioned fastener has the face adjacent the rail recessed to form a seat 16 for the reception of a cushioning member 17 which is interposed between said rail and said fastener. Said head 15 also has its lower portion adjacent the plate cut away or recessed as shown at 18 to receive the flange of the rail. This cushioning member 17 is preferably in the form of a key and is constructed of a

hard wood block substantially square in cross section and of a length slightly greater than the length of said head. One face of the block or key 17 is seated in said recess 18 while its opposite face abuts the web of the rail on the opposite side thereof from the head 8 of the fastener 7.

As hereinbefore mentioned the fastening member 9 is secured to the tie plate by the pivot bolt 11 which not only serves to clamp it in position when the nut 13 is tightened but which also permits it to swing around away from the rail when the nut is loosened. This swinging movement of the fastening member 9 is limited in one direction by a stop lug 19 formed on the plate 5 adjacent one edge as clearly shown in Fig. 3. A second stop lug 19' is formed on the plate near its other side and this lug has a cut-away corner 19'' which permits the fastening member 9 to clear it when such member swings on the pivot bolt 11. The two lugs 19 and 19' have flat upright faces as clearly shown in Fig. 3 engaged by one side or flange of the rail base when the rail is in position on the plate and in order to hold the rail in its proper position shown in Fig. 1 blocks 17 are inserted between the rail web and the fastener 9 as explained above, such blocks being preferably though not necessarily of hard wood. It is also to be noted that the stop lugs 19 and 19' extend only a slight distance above the surface of the plate 5 and therefore do not interfere with the placing of the rail in its proper position.

As a cushioning means for the plate 5 we provide a cylindrical casing 20 having therein a helical expansion spring 21 directly beneath the center of each of the plates. The lower portion of the casing 20 is provided with apertured attaching lugs 22 by which it is riveted or otherwise secured to the bottom 2 of the tie 1 as shown in Figs. 2 and 5. The upper end of the spring 21 contacts with the lower face of the plate 5 and receives a depending boss 23 which extends therefrom and is adapted to maintain said spring in operative position and prevent shifting thereof. The upper edge of the casing 20, however, is spaced from the lower face of the plate 5 and adapted to form a stop to limit the downward movement of said plate when pressure is exerted on the rails R. The spring 21 will not only absorb the shock but the tie itself being formed of spring steel springs slightly under pressure and also acts as a cushioning means to absorb the shocks received by the plate 5. It will be readily seen that the sides 3 of the tie will spring outwardly very readily because of their outwardly inclined position.

An important feature of the invention resides in the making of the channel shaped

or substantially U-shaped tie of steel or other spring metal and arranging its sides so that they bow sufficiently to take up shocks and jars incident to the passing of trains, and also in the use in such tie of the auxiliary cushioning means consisting of helical springs arranged in the tie beneath the tie plate 5. These auxiliary spring devices aid the resilient tie structure in absorbing the shocks and thereby stiffening it sufficiently to sustain the load; and at the same time said auxiliary devices serve as stops to limit the spring action. This is accomplished by the tie plates 5 coming in contact with the upper ends of the casings 20 when undue shocks are received thus preventing the ties from collapsing.

It will be noted that another improved feature of our invention resides in the means for permitting the track rails to be quickly detached from the tie without removing any nuts from bolts, this being accomplished by merely driving the blocks 17 out from between the rail and fasteners 9 and then loosening the nuts 13 sufficiently to permit the fastening members 9 to swing on their pivot bolts 11 as will be readily understood on reference to the drawings.

From the foregoing description taken in connection with the accompanying drawings, it will be readily seen that we have produced an extremely simple yet very strong and lasting tie structure which will tend to absorb the shocks received by the rails from the passing train. It is also obvious after an examination of the accompanying drawings that we have invented a very simple and improved rail fastening means for coaction with the improved tie structure.

We claim as our invention:

1. In a device of the class described, a U-shaped tie of spring metal, a tie plate supported on said tie to carry the rail, and rail fasteners on said plate, said tie springing slightly under pressure to produce a cushioning effect.

2. In combination, a channel-shaped tie of spring metal open at its ends and of the same cross sectional shape throughout its length, said tie having its channel disposed upwardly, the sides of said tie being normally flat and extended upwardly and outwardly, said sides bowing outwardly under pressure, a rail supporting plate rigidly secured to the free edges of said sides to prevent the same from spreading, and a spring device arranged in the tie beneath said plate for the purpose set forth.

3. In combination, a channel-shaped tie of spring metal open at its ends and of the same cross sectional shape throughout its length, said tie having its channel disposed upwardly, the sides of said tie being normally flat and extended upwardly and out-

wardly, said sides bowing outwardly under pressure, a rail supporting member secured to the upper edges of the sides of the tie to prevent said edges from spreading, and a 5 combined stop and cushioning device arranged in the tie, said device becoming active when the sides of the tie are bowed outwardly.

4. In a device of the class described, a tie, 10 a tie plate resting thereon, a cylindrical casing disposed beneath said plate, the upper end of said casing being spaced from the bottom thereof, a helical expansion spring within said casing to absorb the shocks received by said plate, the upper edge of the casing acting as a stop to limit the downward movement of the plate, and rail fastening elements on said plate.

5. In a device of the class described, a 20 U-shaped tie of spring metal, a casing resting on the bottom of said tie, a tie plate resting on the upper edges of said tie over the casing, a helical spring in said casing and contacting with said plate, said spring and tie giving under pressure to absorb the shocks received by the plate, and rail fastening elements on said plate.

6. In a device of the class described, a 30 U-shaped tie of spring metal, a tie plate resting on the upper edges of said tie, a casing resting on the bottom of said tie below said plate, the upper edges of said casing being spaced from the bottom of said plate, a helical spring in said casing contacting with 35 said plate, said spring and tie giving under pressure to absorb the shocks received by the plate, the upper edges of said casing acting as stops to limit the downward movement of the plate, and fastening elements 40 on said tie plate.

7. In a device of the class described, a tie, 45 a tie plate, a rail fastening secured thereto against movement on one side of the rail, an additional fastener on the other side of the rail removably held to said plate against

transverse movement, and a stop lug on the plate on each side of the last mentioned fastener, one preventing rotational movement of the fastener in one direction and the other lug having a cut-away corner for the 50 purpose set forth.

8. In combination, a rail, a tie, a tie plate, a rail fastener permanently fixed on said plate to engage one side of the track rail, an additional rail fastener pivotally mounted 55 on said plate and a locking member interposed between the rail and the inner end of said additional fastener to prevent the latter from turning on its pivot.

9. In combination with a rail, of a tie 60 underlying the same, a tie plate interposed between said rail and the tie, a rail fastener secured to said plate on one side of the rail, an additional fastener on the other side of the rail and removably secured to said plate, 65 one of said fasteners having a recess in its face adjacent the rail and a block of cushioning material lying in said recess and contacting with the web of the rail.

10. In combination, a rail, a tie, a tie 70 plate, a rail fastener permanently secured to said plate to engage one side of the rail, an additional rail fastener pivoted to said plate, a pair of rail engaging stop lugs on the plate on opposite sides of said pivoted 75 fastener, one lug limiting the rotation of said fastener in one direction and the other having a cut-away corner and a locking member removably arranged between one side of the rail and said additional fastener 80 to hold it against rotation.

In testimony whereof we have hereunto set our hands in presence of two subscribing witnesses.
